(57) **CLAIM**

The ornamental design for a display panel portion with a computer generated icon, as shown and described.

DESCRIPTION

The FIGURE is a front view of a display panel portion with a computer generated icon showing my new design. The outer broken line rectangle illustrates the display panel portion and forms no part of the claimed design. All other broken lines illustrate portions of the computer-generated icon and form no part of the claimed design.

1 Claim, 1 Drawing Sheet
